FIRE EXTINGUISHER

James C. Eckert, Jr., Jacksonville, Fla.

Application August 2, 1941, Serial No. 405,256

8 Claims.

(Cl. 169—28)

My invention relates to improvements in fire extinguishers of the explosive type, the principal object in view being to provide a device of this character particularly equipped for pointing, or aiming, at objective areas, or fire zones, and firing while held in the hands to expel fire extinguishing compound therefrom.

Other objects are to provide a device of the character and for the purpose above set forth which is designed for easy reloading, economy in manufacture, easy handling and reliability in operation.

Other and subordinate objects are also comprehended by my invention, all of which, together with the precise nature of my improvement, will be readily understood when the succeeding description and claims are read with reference to the drawing accompanying and forming part of this specification.

In said drawing:

Figure 1 is a longitudinal section shown partly in elevation of a preferred embodiment of my invention.

Figure 2 is a fragmentary view in longitudinal section of a modification of the invention.

Figure 3 is a fragmentary view in longitudinal section illustrating the manner in which the cartridges are capped while detached.

Figure 4 is a view similar to Figure 1 and showing another modification of the invention.

Referring to Figure 1 of the drawing, my improved fire extinguisher in its preferred embodiment thereof comprises an elongated handle-forming barrel 1 of any suitable metal tubing having its butt end closed by a crown-type cap 2 threaded thereon and centrally apertured, as at 3, for a purpose presently apparent. Wedged into the front end of the barrel 1, with a drive fit, and flush with said end of said barrel is a plug 4 having an axial internally threaded bore 5 in which is threaded one end of a coil spring 6 extending from said plug well into the barrel 1. Slidably fitted in the spring 6 is a firing pin 7 having a pointed blunt leading end 8 and to the butt end of which the other end of the coil spring 7 is permanently connected as by extending the terminal thereof through a transverse bore 9 in said butt end of said pin and upsetting said terminal as at 10. A pull rod 11 pivoted at one end in an ear 12 on the butt end of the pin 7, is slidably extended out of the cap 2 by way of the aperture 3 and equipped with an outer end hand grip knob 13.

A cylindrical cartridge holder 14, substantially larger in diameter than the barrel 1, extends forwardly, axially therefrom, said holder having an open front end and a closed rear end provided with an internally threaded annular coupling collar 15 into which the front end of the barrel

1 is screwed, whereby said holder is detachably secured to said barrel.

The cartridge holder 14 is designed to contain a cylindrical cartridge 16 of relatively thinner material having a permanently closed butt end 17 and an open front end closed by a cap 18 frictionally fitted thereover. The cartridge 16 is of a diameter to fit slidably in the holder 14 with its butt end 17 flat against the butt end of said holder and the cap end thereof extending out of the holder. Inwardly of the cap 18, the cartridge 16 is externally threaded, as at 16' for turning into threads in the outer end of the holder 14. An internal annular flange 19 is provided on the butt end of the cartridge 16 axially thereof and of the barrel 1, and which together with the butt end 17 of the cartridge, and a pair of opposed discs 20 of wadding fitted in said flange, forms a chamber 21 for powder or other explosive 22. The cartridge 16 is packed with any suitable fire extinguishing powder or other pulv-erulent compound designated A.

An annular ring 23 having a flanged rim, as at 24, is extended through the butt end 17 of the cartridge 16 axially of the barrel 1 directly below the firing pin 7, said ring extending into the powder 22 in the chamber 21 and functioning as a cap holder. A suitable percussive cap 25 is fitted frictionally in the ring 23 to be fired by the firing pin 7.

As will be seen, the cartridge 16, together with the explosive chamber 21, ring 23 and cap 25, form a manufacturing unit which can be loaded into the holder 14 so that one that has been used may be easily replaced. A suitable detachable cap 26 (Fig. 3) similar to cap 18 may be provided for the butt end 17 of the cartridge 16 to cover and protect the cap 25 of the units before it is loaded into the holder 14.

The use and operation of the described embodiment of my invention will be readily understood. The extinguisher is grasped by the barrel 1 and pointed at the fire area desired to be extinguished, the firing pin 7 is pulled back in opposition to the spring 6 by means of the hand grip knob 13 and pull rod 11, and the knob released. Upon release of the knob 13, the firing pin 7 is projected by the spring 6 through said spring and against the percussive cap 25, thereby exploding the powder 22 in the explosive chamber 21, with the result that wadding 20 is blown out of said chamber 21 and the powder A blown out of the cartridge 16 thereby blowing the closing cap 18 off said cartridge. By unscrewing the empty cartridge 16, it may be removed and a new one loaded into the holder 14.

In the modification of the invention shown in Figure 2, the ring 23 and cap 25 are eliminated, and a fuse 27 inserted through the butt end of the cartridge holder 28 and the cartridge 29 into

the explosive chamber 30 which is closed by an unbroken butt end provided on said cartridge in this instance.

In the modification shown in Figure 4, a cartridge 31, similar to cartridge 16, but of thicker material, is secured at its butt end 32 to the barrel 33 by a coupling collar 34 in the same manner as holder 14 and is equipped with an explosive chamber 35 and percussive cap 36 just as in the case of cartridge 16. The front end of the cartridge 31 has permanently secured therein a flanged annular holder 37 for a disc 38 of frangible material secured by a keeper ring 39 in the holder. As will be apparent in this embodiment of the invention, the outside holder 14 of the preferred embodiment is dispensed with and the cartridge attached directly to the barrel for removal and replacement as a separate manufacturing unit. As will also be obvious, the disc 38 is designed to be broken under the force of the explosion to release the extinguishing powder, designated B, from the cartridge. The cartridge 31 may be capped prior to attachment in the same manner as described with reference to the cartridge 16.

The foregoing will, it is believed, suffice to impart a clear understanding of my invention without further explanation.

Manifestly, the invention is susceptible of modification in other respects than as herein set forth, and right is reserved to such other modifications as fall within the scope of the subjoined claims.

What I claim is:

1. In a fire extinguisher of the class described, a tubular handle, a cylindrical cartridge holder extending axially from one end of said handle and having an open end, a cartridge loaded with fire extinguishing material and detachably mountable in said holder so as to protrude but slightly beyond the open end thereof, means in said cartridge near the inner end thereof forming a rupturable explosive containing chamber, and explosion initiating means in said handle adapted to cooperate with said initiating means to ignite the explosion in said chamber.

2. In a fire extinguisher of the class described, a tubular handle, a cylindrical cartridge holder extending axially from one end of said handle and having an open end, a cartridge loaded with fire extinguishing material and detachably mounted in said holder so as to protrude but slightly beyond the open end of said holder, means in said cartridge adjacent to its inner end forming a rupturable explosive containing chamber and explosion initiating means in said chamber comprising a percussive cap, a firing pin and a spring.

3. In a fire extinguisher of the class described a handle forming barrel of tubular form, a cylindrical cartridge extending axially from one end of said barrel, and loaded with pulverulent fire extinguishing material said cartridge having a butt end opposed to said end of the barrel, means in said cartridge adjacent said butt end forming a rupturable explosive containing chamber, means to ignite explosive in said chamber from the exterior of said cartridge, said cartridge having a closure cap frictionally fitting on the other end thereof for detachment under the force of the explosion incident to igniting said explosive.

4. In a fire extinguisher of the class described

a handle forming barrel of tubular form, a cylindrical cartridge extending axially from one end of said barrel, and loaded with pulverulent fire extinguishing material said cartridge having a butt end opposed to said end of the barrel, means in said cartridge adjacent said butt end forming a rupturable explosive containing chamber, means to ignite explosive in said chamber from the exterior of said cartridge, said explosive chamber comprising an annular flange, and blow out discs of wadding fitting in said flange and retaining the explosive therein.

5. In a fire extinguisher of the class described a handle forming barrel of tubular form, a cylindrical cartridge extending axially from one end of said barrel, and loaded with pulverulent fire extinguishing material said cartridge having a butt end opposed to said end of the barrel, means in said cartridge adjacent said butt end forming a rupturable explosive containing chamber, means to ignite explosive in said chamber from the exterior of said cartridge, said cartridge having a closure cap frictionally fitting on the other end thereof for detachment under the force of the explosion incident to igniting said explosive, and a cylindrical holder for said cartridge detachably attached at one end to said one end of said barrel and having an open opposite end, said cartridge being threaded into said holder.

6. In a fire extinguisher of the class described, a handle, a cylindrical cartridge holder having an open end and a butt end secured to one end of said handle a cartridge detachably mountable in said holder in contacting relation therewith and loaded with fire extinguishing material, means in said cartridge adjacent to said handle forming a rupturable explosive-containing chamber, explosion initiating means in said chamber, said holder enclosing said cartridge substantially over the entire length thereof and actuating means carried by said handle adapted to excite said initiating means for igniting the explosive in said chamber.

7. In a fire extinguisher of the class described, a handle, a cylindrical cartridge holder having an open end and a butt end secured to one end of said handle a cartridge detachably mountable in said holder in contacting relation therewith and loaded with fire extinguishing material, means in said cartridge adjoining said handle forming a rupturable explosive containing chamber, said holder enclosing said cartridge over substantially the entire length thereof, a percussion cap in said cartridge, and actuating means carried by said handle arranged to excite said cap to ignite the explosive in said chamber.

8. In a fire extinguisher of the class described comprising a handle, a cylindrical cartridge holder having an open end and a butt end secured to one end of said handle a cartridge, detachably mountable in said holder in contacting relation therewith and loaded with fire extinguishing material, means in said cartridge adjoining said handle forming a rupturable explosive containing chamber, said holder enclosing said cartridge over substantially the entire length thereof, a percussion cap in said cartridge, and a spring actuated striking pin mounted in said handle and adapted to strike said cap for igniting the explosive in said chamber.

JAMES C. ECKERT, JR.
